UNITED STATES PATENT OFFICE.

ROBERT T. BURCHELL, OF TRENTON, NEW JERSEY.

HOSE-MACHINE.

SPECIFICATION forming part of Letters Patent No. 571,261, dated November 10, 1896.

Application filed April 7, 1896. Serial No. 586,557. (No model.)

To all whom it may concern:

Be it known that I, ROBERT T. BURCHELL, a citizen of the United States, and a resident of Trenton, in the county of Mercer and State of New Jersey, have invented certain new and useful Improvements in Hose-Machines; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a front view of a machine embodying the invention. Fig. 2 is a plan view of the same. Fig. 3 is a transverse vertical section on the line $x-x$, Fig. 1. Figs. 4 and 5 are detail views of the mandrel-center, for one end of the mandrel. Fig. 6 is a similar view of the center for the other end of the mandrel. Fig. 7 is a detail sectional view of the reel-carrier. Fig. 8 is a detail view of one of the slides H^3 and its boxes, and Fig. 9 is a detail view, partly in section, showing the hanger J and a portion of the screw-shaft which carries it. Fig. 10 is an end view looking from the left-hand end of Fig. 2. Fig. 11 is a detail view of one of the cutters. 30 The object of this invention is to provide a hose-machine of improved character; and it consists in the novel construction of parts, all as hereinafter described, and pointed out in the appended claims.

35 Referring to the accompanying drawings, the letter A designates the bed of the machine, which rests upon legs A' or other suitable supports.

40 B designates a head-block at one end portion of the bed, in which and in a bearing B' is journaled a short shaft B^2 .

B^3 is a driving-pulley loosely journaled on said shaft and having a clutch-hub B^4 .

45 B^5 is a clutch-section which is fixed to the said shaft, but is slidable endwise thereon into and out of engagement with the clutch-hub B^4 .

B^6 is a fork which engages the said clutch-section B^5 .

50 B^8 is a compound shifting lever which is connected to said fork. The section B^8 is pivoted and one of its arms has a mitered end

which engages the correspondingly-mitered end of the section B^7 , which is directly connected to said fork.

55

C designates a mandrel, the head end of which has a squared portion c , in which is formed the bearing. The opposite end of the mandrel has a bearing on one of the centers now to be described. C' C^2 are the two centers which carry said mandrel and on which it revolves, the former being on the end of the shaft B^2 and the latter journaled in a movable tail-block C^a at the opposite end portion of the bed.

60

65 Fitted over the center C' , which is the driving-center, is a cap C^3 , which has an angular socket therein of tapering form, its front end being larger than its inner or rear end, which is of the size of the squared portion c of the mandrel. The center C^2 has a half-funnel-shaped cap C^4 . In putting the mandrel in place its squared end is inserted into the cap C^3 and the other end is dropped into the cap C^4 . C^5 is a collar secured adjustably on the center C^2 .

70

75 C^6 is a stout spring whose lower end is secured to the tail-block C^a and whose upper end portion presses against the said collar for the purpose of holding the center C^2 to the mandrel, or rather to hold the mandrel against both centers. The collar C^5 acts as a stop to prevent the said spring from exerting too much pressure upon the mandrel.

80 C^7 is a lever fulcrumed to the tail-block C^a and whose upper arm is connected to the spring C^6 . C^8 is a cord which connects the lower arm of this lever with a treadle C^9 . C^{10} is a bearing-pulley for the said cord.

85 D are two rearwardly-curved arms which are firmly secured to the rear side of the bed A and which support a shaft D' , which is parallel with the mandrel and of about the same length. Secured on said shaft by set-screws or otherwise are a series of adjustable collars E , each of which has connected thereto a downwardly and forwardly extending spring-arm E' , the lower end of which has a fork E^2 , provided with bearings for a small roller E^3 .

90 The arms E are so disposed, as seen in Fig. 2, as to cause the rollers E^3 to break joints with each other.

95 F is a rearwardly-extending counter-weighted arm which is adjustably sleeved on

the shaft D' and is secured by a set-screw. F' is a forwardly and downwardly extending lever which is similarly secured to said shaft at the opposite end portion.

5 G G are two arms which are secured to the shaft D' by collars and set-screws, one of said arms being at each end of the series of rollers. The forward ends of said arms terminate adjacent to the mandrel and are provided 10 with clamps G', in which are secured cutters G'.

H is a stand or table which is placed at the front of the machine and over which the duck or other material is fed to the mandrel.

15 H' H' are two parallel rollers which are journaled longitudinally in the said table. H² is a third roller which is journaled above the front roller H' in vertically-movable slides H³, whereby said roller may be raised or lowered. These three rollers serve as tension-rollers to govern the feed of the duck and prevent it from lapping over while it is being fed to the mandrel.

20 The slides H³ work in the boxes H⁴. (See Fig. 1.) Connected to the lower end portion of each slide is a cord H⁵. These cords extend up through the grooves h of the boxes H⁴, and, passing over the bearing-pulleys h', are connected to a treadle H⁶.

25 30 The rear edge of the table H has, adjacent to the mandrel, an edgewise-disposed piece or flange h⁸, over which the duck after it leaves the rollers H' H² is fed to the mandrel.

35 Journaled over the mandrel in standards I is a rotary shaft I', having cut thereon a helical thread i of considerable depth. Said shaft is driven by a belt or other connection with the shaft B², as indicated.

40 J is a hanger in which is journaled a wire-holding reel K. Said hanger consists of a semicylindrical traveler in whose concave face is cut a thread k, which fits the thread of the shaft J'. Cast on the upper surface of this traveler are two lugs k', having each a bearing in which is a set-screw k². The two lateral portions of the hanger or reel-carrier have hooked upper end portions which extend under the lugs k' and are secured by the said screws. (See Figs. 1 and 9.) Connecting the 45 50 said lateral portions a short distance above their lower ends is an adjustable cross-piece K², having therein a wire-guide k⁴.

55 The reel K is journaled upon a bolt k⁵. On the headed end of said bolt is a sleeve-collar k⁶ and at the opposite end is a thumb-screw k⁷. When said screw is turned in the right direction, the head of the bolt is drawn against the collar I and the latter against the frame of the hanger. In this manner the reel may 60 be put under more or less friction to regulate the feed of the wire therefrom.

65 The operation of the machine is as follows: The lever F' is thrown up, thereby raising all the line of rollers E³. The foot is now placed on the treadle H⁶, thereby raising the slides H³ and the roller H². The rubber tube to be wound having been slipped upon the man-

drel, the latter is placed upon its centers, to permit which the treadle C⁹ is depressed. The foot is now removed, and the center C² 70 closes upon the mandrel. The edge of the duck with which the tube is to be wrapped is now brought to the tube and the treadle H⁶ is released to permit the roller H² to drop. The rollers E³ are now lowered. The lever 75 F' in dropping comes in contact with the compound shifting lever, which action, by means of the mitered contact of the two sections of the said levers, throws the clutch in gear and sets the mandrel in motion. The duck now 80 commences to wind upon the tube. During the winding the lever F' is pressed down with considerable force, causing the rollers E³ to exert pressure on the duck as it is wound, their spring-arms permitting them to yield 85 to seams and other irregularities thereof.

When the duck has been wound, the lever F' is thrown up, which releases the shifting lever. The clutch is now thrown out of operation by means of a suitable spring, as S. 90

95 The knives or cutters, before described, having been set at the required distance apart, the hose will have been cut thereby during the winding to the required length. The mandrel is now removed. In the operation as thus described the screw-shaft I' is thrown out of operation, being used only in the operation of winding and applying the cord in making corrugated hose. In this operation, the screw-shaft being revolved, the 100 hanger which carries the reel is fed along said shaft by its rotation. The wire is delivered to the mandrel, one ply of duck is wound over the wire, and a gum tube is placed over the duck. Another ply of duck is then wound, 105 another of gum, then a wrapping of muslin, after which the cord is applied.

I desire to state that I do not limit myself to the exact construction and arrangement of parts as herein shown and described, it being 110 obvious that these may be varied somewhat without departing from the spirit and scope of my invention.

Having thus described my invention, what I claim as new, and desire to secure by Letters 115 Patent, is—

1. In a hose-machine, the combination with the removable mandrel, and means for supporting and rotating the same, of a shaft adjacent to the mandrel, a series of adjacent 120 spring-arms carried by said shaft and having at their free ends bearings which are adjacent to said mandrel, and a short roller journaled in the bearings of each of said arms, together with means whereby said arms with their 125 rollers may be moved toward and away from the mandrel, substantially as specified.

2. In a hose-machine, the combination of the mandrel, and mechanism for rotating the same, a counterweighted shaft journaled 130 above and to the rear of said mandrel, the series of collars adjustably secured thereto, the series of spring-arms carried by said collars, and the series of rollers journaled at the

free end portions of said arms, adjacent to the said mandrel, substantially as specified.

3. In a hose-machine, the short driving-shaft having a center bearing at one end, and having a cap secured over said center, said cap having an angular-tapered socket, of a mandrel having a squared end adapted to fit the said socket, a center bearing at its opposite end, a short centering-shaft for said bearing, a half-funnel-shaped cup on said shaft adapted to receive the mandrel end, a spring for holding said centering-shaft in contact with the mandrel, and means for withdrawing said centering-shaft out of contact with the mandrel, substantially as specified.

4. In a hose-machine, the combination of the mandrel, its driving and centering shaft, the pulley on the driving-shaft, the clutch mechanism, the compound shifting lever, the counterweighted shaft, the series of spring-roller-carrying arms adjustably secured to said shaft, and the lever also secured to said shaft, and adapted, when depressed, to engage and actuate the shifting lever to throw the clutch mechanism into operation, substantially as specified.

5. In a hose-machine, the combination with the removable mandrel, the rock-shaft journaled adjacent to said mandrel, a series of spring-arms carried by said shaft and terminating at their free ends in bearings, forks adjacent to the mandrel, and a short roller journaled in each of the said forks, the series of rollers so journaled being arranged to break joints with each other, substantially as specified.

6. In a hose-machine, the combination with

the mandrel, of the feed-table having the parallel rollers H', H', the roller H² above one of the rollers H', the vertically-movable slides 40 in which the roller H² is journaled, a treadle, and connections between the treadle and the said slides whereby they may be raised, substantially as specified.

7. In a hose-machine, the combination with 45 the removable mandrel, the driving - shaft therefor, the endwise-movable treadle-operated centering-shaft, the feed-rollers for said mandrel, the counterweighted rock-shaft adjacent to the mandrel and behind the same, 50 the series of spring - arms carried by each shaft, and having each at its free end portion, adjacent to the mandrel, a loosely-journaled short roller, the cutter-carrying arms carried by the same shaft as the spring-arms, 55 and the cutters, substantially as specified.

8. In a hose-machine, the combination with a revolving mandrel, of a shaft journaled parallel therewith and formed with a helical thread, the semicylindrical traveler engaging 60 said shaft and supported and traveling thereon, the hanger having lateral arms whose upper ends are secured to the top portion of the said traveler a roll journaled in said hanger, and means for putting the axis of said roll 65 under more or less friction, substantially as specified.

In testimony whereof I affix my signature in presence of two witnesses.

ROBERT T. BURCHELL.
